UNITED STATES PATENT OFFICE.

ISAAC BURNETT AND ELMER FOLLIOTT, OF JOLIET, ILLINOIS.

SLIP-RAIL FROG FOR RAILROADS.

SPECIFICATION forming part of Letters Patent No. 349,689, dated September 28, 1886.

Application filed May 17, 1886. Serial No. 202,419. (No model.)

To all whom it may concern:

Be it known that we, ISAAC BURNETT and ELMER FOLLIOTT, citizens of the United States of America, residing at Joliet, in the county of Will and State of Illinois, have invented certain new and useful Improvements in Slip-Rail Frogs for Railroads, of which the following is a specification, reference being had therein to the accompanying drawings.

10 This invention relates to certain improvements in slip-rail frogs for railroads, which improvements are fully set forth and explained in the following specification and claims, reference being had to the said drawings and the 15 letters and figures thereon, forming a part of this specification, similar letters of reference indicating corresponding parts in all the figures.

Referring to the said drawings, Figure 1 is 20 a perspective view of a main track and side track of a railroad, showing the frog and its operating attachments as it would appear in service. Fig. 2 is a plan view of a section of a railroad-track, showing the slip-rail frog of 25 the switch and the immediate parts for operating said slip-rail. Fig. 3 is a horizontal sectional view of the cranked sheave-wheel of the secondary switch-stand, taken on a line at the side of its peripheral cable-groove. Fig. 4 is a 30 vertical central cross-section of the secondary switch-stand and its sheave-wheel. Fig. 5 is a plan view of the lower plate of the secondary switch-stand, to show its segmental slot. Fig. 6 is a side view of one of the bolts for securing 35 the parts of said switch-stand together. Fig. 7 is a perspective view of one of the tubular supporting-studs of said switch-stand. Fig. 8 is a plan view of a section of a railroad-track, showing the point switch-rails and the immediate 40 parts for operating them. Fig. 9 is a side view of an automatic switch-stand having a portion of its base broken away to show its interior mechanism. Fig. 10 is a cross-section of Fig. 8, taken on line 2, looking in the direction of the arrow. Fig. 11 is a horizontal section of a portion of the slip-rail of the frog, taken on a line immediately below the tread 45 of the rails, showing the manner of the attachment of the slip-rail to the two converging track-rails forming the frog-point. Fig. 12 is a bottom plan view of a portion of the supporting-plate of the frog, showing the manner

of the attachment of the slip-rail to it. Fig. 13 is a horizontal sectional view of a portion of the two converging track-rails forming the 55 frog-point, taken on a line immediately below their tread to show their socketed end, to which the slip-rail joints. Fig. 14 is a horizontal sectional view of a portion of the slip-rail of the frog, taken on a line immediately below its 60 tread, showing its rounded heel end, which joints to the socketed end of the frog-point. Fig. 15 is a perspective view of the forked fish-plate for attaching the slip-rail to the frog-point pivotally. Fig. 16 is a cross-sectional 65 view of Fig. 2, taken on line 3, looking in the direction of the arrow. Fig. 17 is a side view of one of the auxiliary supporting-rails, showing a section of a fixed track-rail and of the slip-rail and a section of their supporting plate. Fig. 18 is a view of the socketed end of the 70 frog-point, showing the recess between them for the reception of the fish-plate for connecting it pivotally with the slip-rail. Fig. 19 is a cross-sectional view of the slip-rail and its 75 supporting bed-plate, taken on line 4 of Fig. 12, looking in the direction of the arrow. Fig. 20 is a perspective view of the plates for holding and connecting the slip-rail to its supporting-bed; and Fig. 21 is a view showing a pair 80 of arms for substituting the sheave-wheels and of a pair of rods for substituting the wire cables.

In the drawings, R R represent the parts of the main track, and R' R' the rails of a side 85 track, one of each terminating in the two pointed switch-rails O and O' connected by means of the tie-rods Z Z.

P is a supporting-plate forming the base of the frog, supporting at one end the converging 90 ends of both a main and side track rail forming the frog-point, and supporting the separated ends of a main and side track rail at its opposite end.

S is a slip-rail resting on said plate P, and 95 having its heel pivotally socketed to the frog-point, and its opposite toe end free to move laterally to form either a section of the main or side track, as may be desired. The frog-point is socketed, as shown at S' in Figs. 2, 100 11, 12, and 14, to receive the rounded form S' of the heel of the slip-rail S.

The manner of pivotally attaching the heel of the slip-rail to the frog-point is shown par-

ticularly in Fig. 11, by means of the forked fish-plate J, shown in perspective in Fig. 15, to show its exact form. The forked end of said fish-plate forks over the web at the slip-rail at its heel, and is secured thereon by means of bolts passing through, as shown, while its opposite shanked end enters the chamber in the frog-point, as shown in Fig. 11. This chamber is formed by the space between the two rails forming the frog-point, and is shown particularly in Fig. 18. The form of said chamber diverges so its rearward part is wider than its front part, so the end of the fish-plate therein may have some lateral movement to permit lateral movement of the toe of the slip-rail. Said slip-rail also attaches to the supporting-plate P, as shown in Figs. 12 and 19. Said plate is provided with a segmental transverse slot, N, immediately beneath said slip-rail near its heel for the reception of the segmental slide N', placed between said slip-rail and the plate N², and the three parts are held together by means of rivets or bolts, as shown in Fig. 19. The length of slot N permits lateral movement of the slide N' therein when the slip-rail to which it is attached is moved, and by this means an additional fastening of the slip-rail to said supporting-plate P is obtained. A pair of auxiliary supporting-rails, c c, are attached to said plate P by means of rivets, and bolted, respectively, to the outside of the end of both the main and side track rails, as shown in Figs. 2, 16, and 17, and so they overlap the joint between said rails and the toe of the slip-rail, as shown in Figs. 1, 2, and 17, to bear the weight of the car-wheels at said joint, and more particularly furnish a backing to said slip-rail and hold it firmly in place. The toe of the slip-rail S connects through the medium of connecting-rod B with the crank-pin G' on the lower face of sheave-wheel W' of the switch-stand H, as shown in Figs. 1, 2, 3, and 4, and the pointed ends of the switch-rails O and O' are connected through the medium of rods m and m' with crank-pin G on the lower face of sheave-wheel W of the automatic switch-stand T, as shown in Figs. 1, 8, 9, and 10. The said sheave-wheels are connected by means of the wire cables D D. These cables have screw-threaded shanks b on their ends for passing through the integral lugs t of said sheave-wheels for securing them to said sheaves, and to furnish means for giving the proper tension to said cables.

The switch-stand H is shown in detail in Fig. 4, and consists of the two horizontally-arranged plates F and F', bolted to bed-timbers by means of bolts e at each corner, and held separated and above said timbers by means of tubular studs Q, sleeved on said bolts e. The sheave-wheel W' is placed between said plates, and its trunnions d and d' journal centrally in said plates, as shown in said figure and in Fig. 1. The lower plate, F', is provided with a segmental annular slot, G'', for the reception of crank-pin G' on the lower side of said sheave, which crank-pin bears the con-

necting-rod B. The passage of said crank-pin through said slot restricts its rotation to the limits of said slot, and prevents said connecting-rod, which lies on said plate F', from dropping off said crank-pin. This auxiliary switch-stand H may be housed on its sides, as shown in Fig. 1, and in cross-section in Fig. 2, and in such instance the pipes E E screw into the side of said housing, as shown in said figures, in such manner and in such position that the cables D D may pass through them for protection.

Switch-stand T (shown in Figs. 1 and 9) connecting with switch-stand H by means of said cables and the pipes E E, and with the point switch-rails of the track, is what is termed an "automatic switch-stand," for the reason that its construction permits the flanges of the wheels of a passing car to move the switch-rails and slip-rail when by accident they are left set for the wrong track, as will be more fully explained hereinafter. The construction of said switch-stand T is substantially as follows:

K is a stationary base fixed to bed-timbers. Within this base is perpendicularly arranged a shaft, v, boxed in a cross-plate near its lower end, and in a feathered clutch, I', located within and near the top of said base, said clutch being yieldingly supported by means of a coil-spring sleeved on said shaft, and resting on the box near the lower end of said shaft. A head, I, is placed on the top of said base, and is provided with a depending clutch arranged to clutch with feathered and yielding clutch I'. This head is provided with a square socket for the reception of the square shank I² depending from a sliding head sleeved on square shaft y, which is integral with and a continuation of shaft v. The lever h is pivotally secured to a sleeve on shaft y and connected with said shanked head by means of a link, L. When said lever is raised, shank I² will be raised and disconnected from head I, and the shaft y v may then be rotated to operate the switch independently from and without moving the said clutches; but when the said lever is down and said shank is socketed in head I, said shaft cannot turn without turning head I with it, and if the said shaft is then turned it must be done under pressure or strain on sheave-wheel W or on a lever, h, and in such instance clutch I' must be depressed on spring sleeved on shaft v to permit its fellow clutch of head I to shift position, the beveled form of said clutches permitting such shift. The auxiliary supporting-rails c c have the ends of their tread rounded or beveled, as shown in Figs. 1, 2, and 17, so they may present an inclined approach for the car-wheels in passing over them, and are for the purpose of giving lateral support to the two fixed track-rails and the slip-rail of the frog, and also to bridge over the point at that place. When the switch is set for the main track, the cranks G and G' of the sheave-wheels W W' are turned so their rail-connecting rod will be on dead-cen-

- ters to hold the switch locked in such position; but when the switch is set for the side track, then the said cranks are turned one-fourth way around to hold said connecting rods midway between dead-centers, so the wheels of a passing car can press the slip-rail S of the frog to one side and automatically set the point switch-rails for the main track through the medium of said switch-stands and cables, should the switch be left set by mistake for the side track. It will thus be seen that the use of the automatic switch-stand is for the purpose of permitting the wheels of a passing train to set the switch right should it be by mistake left open and set for the wrong track. The spring-clutch in said stand is intended to be of sufficient strength to hold the switch set for either track, and prevent its being moved by a passing train on the track for which it is set; but not of such strength as to prevent the wheels of a train on the track for which it is left open from automatically moving the slip-rail and switch-rails, as stated, and set them for the main track, and thereby prevent the train from being derailed. It is not necessary to use this particular kind of automatic switch-stand for this purpose. Any switch-stand that will permit the car-wheels to so set the switch may be used. It is intended that bed-timbers shall be used, laid in or upon the ground, for connecting and properly holding apart the two switch-stands and for supporting the cable-pipes E E, as shown in Fig. 1. If desired, the sheave-wheels W W' may be substituted by the arms W² W², and the cables D D may be substituted by the rods connecting said arms, as shown in Fig. 21. The operation of this switch is as follows, substantially: When it is set to form continuous rails for the main track, then side pressure on the slip-rail will not misplace the switch, as the cranked ends of the connecting-rods connecting the switch-rails and slip-rail with the switch-stands are on dead-centers of their cranks, and cannot be moved until lever h of switch-stand T is raised so its square shank I' will be disengaged from the square socket of head I, when said lever may then be easily turned to rotate shaft y v, as described, to partially rotate cranked sheave-wheels W W' within the limits of the slot in plate F' and operate the connecting-rods connecting said cranks with the switch-rails and slip-rail of the frog, as stated, the pressure of the coil-spring of switch-stand T on clutch I' being too great for the strength of a person to shift the clutch to operate the switch. Should the switch be set for the side track carelessly, and a train should come down the main track, (see Fig. 1,) then of course the train would take the side track, and could be stopped before going far; but should a train moving up the main track (see said Fig. 1) approach the switch when set for the side track, as stated, the flanges of the

locomotive-wheels will move the toe of the slip-rail S to one side and set it for the main track, and also set the switch-rails for the main track, as before described, so the train would not be derailed at the frog or switch.

By the use of an automatic switch-stand, in combination with the slip-rail frog and the auxiliary stand, as described, the common so-called "stub-switch" is rendered automatic and perfectly safe, equally so as a split or point switch, as, when a wheel passes through the slip-rail frog, it will as readily adjust a stub-switch to "safety" as it will a point-switch, as one performs the same service as the other.

Having thus described our invention, what we claim as new, and desire to secure by Letters Patent, is as follows, to wit:

1. In a railroad-switch, a frog-point formed from the converging ends of two fixed track-rails having a recess between them and a socketed point, in combination with the slip-rail S, having its heel pivoted to said frog-point at its socket, and the forked fish-plate J, for connecting said frog-point and slip-rail, substantially as and for the purpose set forth.

2. In a railroad-switch, a frog-point having a socketed point, in combination with a slip-rail jointed thereto at said socket, forked fish-plate J, plate P, having slot N, plate N², and slide N', connecting said plate N² with said slip-rail and traversing said slot, substantially as and for the purpose set forth.

3. The combination, with the fixed railroad-tracks R R and R' R', of pointed switch-rails O and O', slip-rail S, plate P, connecting-rods B m m', switch-stand H, having the cranked sheave-wheel W', automatic switch-stand T, having the cranked sheave-wheel W, and the cables D D for connecting said sheaves, substantially as and for the purpose set forth.

4. In a railroad-switch, the combination, with the fixed rails R R and R' R', of the slip-frog rail S, socketed to the frog-point and held down upon its bed-plate by means of the sliding plate N² secured thereto, of the bed-plate P, and the auxiliary supporting-rails c c, having their treads of equal height with the said fixed rails and inclined at either end, and arranged at the side of and secured to said fixed rails in such manner as to form lateral support for the movable end of said slip-frog rail, substantially as set forth.

5. In combination with an automatic switch-stand, constructed and arranged substantially as shown and described, the secondary switch-stand H, cables D D, for connecting said switch-stands, connecting-rods B, m, and m', point-switch rails O and O', slip-frog rail S, and the fixed track-rails R R and R' R', as and for the purpose set forth.

ISAAC BURNETT.
